UNITED STATES PATENT OFFICE.

HENRY H. RADDE, OF BAY CITY, MICHIGAN.

METHOD OF MAKING RADIATOR CORES.

Application filed April 13, 1922. Serial No. 552,240.

This invention relates to radiators such as used for cooling internal combustion engines and the like.

One object of the invention is to design a 5 radiator core which can be stamped out of suitable metal, and which can be very cheaply manufactured.

Another object of the invention is to design a radiator core so that the front, rear, 10 and side walls can be stamped out of a single piece of metal and then formed to shape.

A further object is to provide a radiator core having a maximum area of cooling surface, which can be easily assembled, and 15 which does not require skilled labor in the manufacture thereof.

A further object still is to provide a radiator core which can be easily and quickly repaired, and in which sections thereof 20 can be closed so that the radiator will properly function even should one section or compartment thereof be damaged.

With the above and other objects in view, the present invention consists in the combination and arrangement of parts, herein-after more fully described, illustrated in the accompanying drawings, and particularly pointed out in the appended claims, it being understood that changes may be made 25 in the form, size, proportion and minor details of construction without departing from the spirit or sacrificing any of the advantages of the invention.

In the drawings:—

Fig. 1 is a part sectional front view of 35 my improved radiator core.

Fig. 2 is a part sectional side view thereof.

Fig. 3 is an enlarged fragmentary detail 40 illustrating the manner of securing the ends of the sheet metal together.

Fig. 4 is an isometric view of one of the tubes.

Fig. 5 is a view of the plate punched, but 45 not formed to shape.

Fig. 6 is a top plan view of the top plate.

Fig. 7 is a similar view of the bottom plate.

Fig. 8 is a view illustrating the bending and forming of the plate.

As stated this invention relates to radiator 50 cores and particularly to a radiator core which can be very cheaply manufactured. The conventional radiator at present used for cooling internal combustion engines installed in automobiles, trucks and tractors 55 are expensive to manufacture, and difficult

to assemble or repair. The disadvantages I have overcome in my improved construction.

Referring now particularly to the drawing in which I have shown the preferred embodiment of my invention, I take a large undeveloped sheet of metal 1, preferably copper, which I stamp to the shape as shown in Fig. 5 of the drawings, a series of openings 2 are punched therein in spaced relation as shown, the section 3 of this sheet forming the front wall of the radiator core, while the section 4 forms the rear wall thereof. This sheet is adapted to be bent on the lines 5 and 6 so that the front and rear walls 65 will be parallel to each other and spaced apart as shown. The section 7 forms the one side of the radiator, the other side being formed by the sections 8 and 9 which are bent at right angles to the main body on the lines 10 and 11 and form an interlocking joint as clearly shown in Fig. 3 of the drawing. Angles 12 are secured to the sides of the radiator by means of rivets or the like 70 and are adapted to support the radiator on the automobile frame. The back wall of the upper radiator tank is formed by bending the section 13 on the line 14, and thence bending the section 15 on the line 16 at right angles to the section 13 and parallel to the 75 front wall, a suitable intake opening being provided and a connection 17 being secured thereto, the lip section 18 is then flanged outwardly as shown being bent on the line 19. 80

The front wall of the radiator is exactly similar, excepting that the section is straight, a lip 20 being provided and is bent outwardly on the line 21. A perforated plate 22 is then secured in position between 85 the walls and forms the bottom of the radiator top tank, the top plate 23 being welded to these outwardly flanged top and side lips as shown. A water inlet 24 is secured to this top plate and is provided with a conventional radiator cap in the usual manner. 100

The bottom is formed identically the same as the top, the lips 25 and 25^a being flanged outwardly and bent on the bending line as indicated in Fig. 5, and the plate 27 is welded thereto. The plate 26 is then welded or soldered in place, and forms the top of the radiator bottom tank, and this plate is also perforated in a similar manner to allow water or other liquids to enter the bottom tank, outlet pipe 28 being connected thereto 105 in the usual manner. 110

The plate is first punched as clearly shown in Fig. 5, and then bent to shape as shown in Fig. 8, of the drawings, the openings 2 in the front and rear walls will then be in direct horizontal alinement, and are adapted to be connected by the tubes 29. These are preferably welded to the respective walls and form passages for the circulation of air for cooling the water circulating through the radiator core.

A vertically disposed division plate 30 is secured between each row of tubes and separates the radiator core into separate and distinct compartments, the openings in the plates 22 and 26 being spaced to allow the water or other liquid to freely flow into each compartment. These tubes can be of any reasonable desired size, and while I have shown but a limited number it will be clearly understood that any desired number can be used. A perforated screen 31 is secured to the front of the radiator by means of the small bolts 32, and serves to break the air current circulating through the tubes and also presents a neat appearance. It is of course understood that this is merely the radiator core, the shell covering and surrounding the core in the usual manner, the usual opening being provided in the front of this shell to allow for proper circulation of air.

From the foregoing description it will be obvious that I have perfected a very simple and improved article of manufacture.

35. What I claim is:—

1. The method of making radiator cores which consists in taking a single sheet of

metal, punching a plurality of openings therein and bending it to shape to form front, rear and side walls, soldering the edges together and then bending a section to form the back wall of the upper radiator tank, then taking a couple of sheets and soldering them on the top in spaced apart relation to form the top tank, and soldering a couple of spaced apart sheets in the bottom to form the lower tank, then securing a number of vertically disposed spaced apart division plates between the walls, and soldering tubes in the openings punched in the front and rear walls, and securing supporting angles to the side walls of the shell.

2. The method of making radiator cores which consists in taking a single sheet of copper forming it to shape, and punching a plurality of spaced apart openings therein, then bending it to form front, rear, and side walls, soldering the edges together, bending a section of the plate to form the back wall of the upper radiator tank, then securing a perforated plate between the front and rear wall and soldering a top plate to said walls to form a top tank, then soldering a pair of plates to the walls near the bottom to form a bottom tank, securing tubes in the openings in the front and rear wall, and a plurality of spaced apart vertically disposed plates between the walls securing inlet and outlet tubes to the top and bottom tanks, and securing supporting brackets to the side walls of the radiator shell.

In testimony whereof I affix my signature.

HENRY H. RADDE,
